ABSTRACT OF THE DISCLOSURE

A fluid pump mounted on a rotating shaft capable of pumping two different fluids independently having multiple axially reciprocating, radially spaced ball pistons, driven in harmonic motion by rotating reaction cams providing multiple strokes per revolution.

Pumps utilizing balls as pistons have been proposed as in U.S. Pat. No. 1,325,434.

A pressure pump utilizing a single rotating cam working on multiple cylinders and pistons is shown in U.S. Pat. No. 2,460,949.

A combination of balls and cams for a hydraulic pump or motor is shown in U.S. Pats. Nos. 3,435,774 and 3,435,775.

SUMMARY OF THE INVENTION

My invention provides an improved method for transforming rotary shaft power into a reciprocating axial motion of a double ball piston without crank shaft and connecting rods. The pump consists of a solid housing journaled on a rotating shaft enclosing two separate pumping chambers. The housing consists of two end plates in which are mounted oppositely biased axially aligned check valves which function as an inlet and an outlet to each of the pumping chambers. Separating the two pumping chambers is a fixed cylinder block containing several axially aligned cylinders connecting the two pumping chambers. Slideably and sealably mounted in each of these cylinders are two free rolling balls. Fixedly mounted on the rotating shafts are two reaction cams, one on each side of the cylinder block aligned so the respective camming surfaces are in rolling contact with one of the balls of the double ball pistons. The high points of one cam surface are aligned opposite the low points of the other cam. As the shaft and the cams rotate the balls roll on the cam surfaces causing the double ball pistons to reciprocate axially which in turn causes the volumes of the pumping chambers to increase and decrease periodically. It is this increasing and decreasing chamber volume which provides the differential pressure necessary to operate the check valves in their proper sequence and to independently pump liquid in and out of the chambers.

For any given shaft velocity, the displacement of the pump can be varied by varying the number of camming slopes, number and size of balls and diameter of the pump. This feature gives great flexibility of design of the pump to achieve a large variety of pumping rates for any given shaft velocity. Since each reaction cam can have a number of high points, the pump is provided with multiple reciprocating strokes per revolution. The simplicity of the design makes construction economical and maintenance easy.

In a preferred embodiment the pump with an internal chamber diameter of only seven inches provides a pumping rate of 4,317 gallons per minute, with a shaft rotating at 3,600 r.p.m.

Other features and advantages of this invention will be apparent from the following description of certain embodiments thereof taken in conjunction with the drawings.

FIG. 1 is a perspective of the fluid pump completely assembled.

FIG. 2 is an exploded view of the same pump with the cams and balls shown together for clarity.

5 FIG. 3 is a side section taken along lines 3—3 of FIG. 1.

FIG. 4 is a front section taken along lines 4—4 of FIG. 3.

FIG. 5 is a perspective of a first alternative form of the 10 pump wherein the intake and discharge ports are rearranged.

FIG. 6 is a side section view taken on lines 6—6 of FIG. 5.

FIG. 7 is a front section taken on lines 7—7 of FIG. 6.

15 FIG. 8 is a section of a second alternative form of the pump wherein the cylinder and balls revolve past stationary cams.

FIG. 9 is a front section taken on lines 9—9 of FIG. 8.

FIG. 10 is a section of a third alternative form wherein 20 the balls travel radially rather than axially.

FIG. 11 is a section taken on lines 11—11 of FIG. 10.

DESCRIPTION OF THE PREFERRED EMBODIMENT

Construction of the pump

A solid housing, 20, encloses two separate pumping chambers 21 and 22. On it is journaled a rotating shaft 40 by means of bearings 30. The housing consists of three parts: two identical end plates 23, and a cylinder block 24. Each of the end plates contains a pair of oppositely biased inlet and outlet check valves, 25, mounted axially as shown. One valve of each pair is spaced 180 degrees away from its mate.

35 Several cylinder bores, 26, are drilled completely through the cylinder block and placed around the circumference of a circle. The cylinder block 24 is provided with axially extending flanges at its outer perimeter so that the assembled housing encloses the two hollow pumping chambers 21 and 22.

40 Slideably and sealably mounted in each cylinder 26 are two balls 27, each allowed to roll freely within the cylinder. When the double ball pistons are placed in the cylinders, the two pumping chambers are isolated by the sealing rings, 28, so that no fluid will pass between them.

45 Fixedly mounted on the shaft on opposite sides of the cylinder block are two cylindrical reaction cams, 31 and 32, each with an equal number of high, 33, and low, 34, points as shown in perspective view, FIG. 2. As mentioned earlier, cam 33 is shown in FIG. 2 adjacent to the balls although its actual position is on the other side of cylinder block 24. The cam surfaces face one another with high points of one being aligned opposite the low points of the other. Each of the cam surfaces has rolling contact with the balls of the double ball pistons on its side of the cylinder block. As the cams rotate, the ball pistons will reciprocate in their cylinders a number of times for each revolution of the cam.

Operation of the pump

60 The shaft rotates under the power of a suitable motor force (not shown). As the shaft, 40, rotates, cams, 32 and 33, which are fixed to the shaft also rotate. FIG. 3 shows the layout of the two cams, the cylinder block, the ball pistons and the check valves in their relationship as they cooperate during operation of the pump. The high point on cam 32 is in frictional rolling contact with one of the balls of the double ball pistons. A low point on cam 33 is in frictional rolling contact with the other ball of the double ball pistons. The cylinder block is fixed with respect to the moving cams. As the two cams begin to move together, the ball which is resting on the

high point of cam 17 begins to roll down into the next adjacent valley. The ball which is rolling in the low point of the cam 33 begins to roll up the next adjacent high point. The rolling cam surfaces transfer an axial force to the double ball pistons which causes the double ball pistons to move axially in the cylinders. As the many high and low points on the cams roll past the pistons, the pistons reciprocate in the cylinders many times for each revolution of the cams.

As can be seen from FIG. 2, all of the pistons move together in the same direction. As the pistons move to the right, the volume in the right hand pumping chamber decreases. This decrease in volume causes a corresponding increase in fluid pressure which operates the outlet check valve for that chamber and forces fluid out of the pumping chamber into the fluid stream. As the volume in the right hand chamber decreases, the volume in the left hand chamber increases, causing a corresponding pressure drop which opens the inlet check valves allowing fluid to enter the left hand pumping chamber from the fluid stream. As the pistons move to the left, the operation is reversed. It is this periodic change in volume of the two pumping chambers that provides the pumping action on the fluid. Since the two pumping chambers are isolated from one another by means of the sealing rings on the ball pistons, the pump is capable of pumping two separate fluids.

MODIFICATIONS OF THE PREFERRED EMBODIMENT

The first alternative form of the pump shown in FIGS. 5, 6 and 7 varies only in having a two way shuttle valve 35 connected to a single intake port 37 and a two way shuttle valve 36 connected to a single discharge port 38.

A second alternative form shown in FIGS. 8 and 9 utilizes a stationary cam element 41 as part of the end plates 43 and 44. The shaft 40 turns cylinder block 45 past these cams.

A third alternative form of the pump is shown in FIGS. 10 and 11. Like the second alternative form cylinder block 46 revolves while internal cam 47 and external cam 48 are stationary. The ball pistons 49 reciprocate radially to effect their pumping action while being revolved around the axis in the cylinder block 46.

Each valve 35 and 36 is connected to each pumping chamber. Inlet shuttle valve 35 prevents back flow during the compression stage of each chamber while allowing the other chamber to fill during the expansion stage. Discharge shuttle valve 36 allows fluid to pass from the chamber in its compression stage but not to flow back into the chamber being filled in its expansion stage.

Any of the foregoing versions of the pump may be used to pump two entirely separate fluids provided that adequate provision is made for fluid seal within the cylinder bore. The drawings disclose a conventional ring seal 28 which may be utilized. Equivalent seals which may also physically separate the two ball pistons are well known and may also be utilized.

Another feature is that the check valve or shuttle valve may be eliminated and a sliding port valving arrangement may be substituted.

Having disclosed my invention in the foregoing specification, I claim:

1. A positive displacement fluid pump
  - (a) two internal fluid chambers,
  - (b) a cylinder block having a plurality of cylinder bores,
  - (c) opposite ends of said cylinder bores communicating with said two internal fluid chambers,
  - (d) a pair of synchronized cooperating cam tracks, each track placed on opposite sides of said cylinder block within each chamber and facing the ends of said cylindrical bores,
  - (e) a pair of piston balls displaced within each of said bores, each of said balls cooperating with one of said cam tracks,
  - (f) said cam tracks and cylinder block in relative rotational motion,
  - (g) said relative rotational motion provided by a powered shaft for said pump,
  - (h) said relative rotational movement providing linear movement of said balls within said cylinder bores,
  - (i) said linear movement of said balls providing cyclical expansion and contraction of each of said fluid chambers whereby a pumping action is effected,
2. The fluid pump of claim 1 wherein a single ball is displaced in each cylinder bore and acted upon by each cam in each chamber.
3. In the fluid pump of claim 1 a shuttle valve connected to both chambers, thereby providing a continuous flow of fluid through one discharge or intake port.
